Primary Examiner — Rhea Shields

(57) **CLAIM**

The ornamental design for a hair removal device, as shown and described.

DESCRIPTION

1. Hair removal device

1.1 : Perspective

1.2 : Front

1.3 : Back

1.4 : Left

1.5 : Right

1.6 : Top

1.7 : Bottom

Fig. 1 is a perspective view of hair removal device showing the new design; Fig. 2 is a front view thereof; Fig. 3 is a rear view thereof; Fig. 4 is a left side view thereof; Fig. 5 is a right side view thereof; Fig. 6 is a top view thereof, Fig. 7 is a bottom view thereof.
